DESIGN FOR A PORTABLE PUMP

Mendel S. Halpern, San Francisco, Calif.

Application November 19, 1934, Serial No. 54,078

Term of patent 7 years

To all whom it may concern:

Be it known that I, Mendel S. Halpern, a citizen of the United States, residing at San Francisco, in the county of San Francisco, State of California, have invented a certain new, original, and ornamental Design for a Portable Pump, of which the following is a specification, reference being had to the accompanying drawing.

Figure 1 is a side elevation of a portable pump showing my new design.

Figure 2 is a top plan view of the same.

Figure 3 is an end elevation, and

Figure 4 is an elevation opposite that shown in Figure 3.

I claim:

The ornamental design for a portable pump, as shown.

MENDEL S. HALPERN.
